UNITED STATES PATENT OFFICE.

GEORGE H. HESS, OF LA GRANGE PARK, ILLINOIS.

WASHING-MACHINE.

1,084,275.

Specification of Letters Patent.

Patented Jan. 13, 1914.

Application filed April 14, 1913. Serial No. 761,075.

To all whom it may concern:

Be it known that I, GEORGE H. HESS, a citizen of the United States, residing at La Grange Park, in the county of Cook and 5 State of Illinois, have invented a new and useful Improvement in Washing-Machines, of which the following is a specification.

My invention relates, more particularly, to improvements in machines for washing 10 dishes; and my objects, generally stated, are to provide a novel, simple and economical construction of dish-washing machine by which dishes may be quickly and effectively cleansed, by which the machine may be 15 quickly charged with, and emptied of, dishes, and the machine readily cleansed of accumulations therein, to render it sanitary, and, generally, to so improve upon constructions 20 of this character that they will be better adapted to perform their work quickly, effectually and at minimum expense.

Referring to the accompanying drawings, Figure 1 is a transverse sectional view of a machine constructed in accordance with my 25 invention, the section being taken at the line 1 on Fig. 2 and viewed in the direction of the arrow; and Fig. 2, a section taken at the line 2 on Fig. 1 and viewed in the direction of the arrow.

30 My improved machine is formed with a shell or casing 3, which is preferably of cylindrical form and supported in any suitable manner, as upon legs 4, the front end 5 of the shell 3 containing an opening 6, 35 preferably of circular contour excepting at its bottom edge which is straight and equipped with a door 7 for affording access to the interior of the machine for charging the latter with dishes and removing them 40 therefrom, as hereinafter stated, the rear end of the shell 3 being closed, as indicated at 8. A tray for receiving the dishes to be washed is represented at 9, this tray, which has a 45 perforated bottom 9^a, being removably supported in the shell 3, and preferably to extend entirely below the center line of the latter, as hereinafter explained.

In accordance with my invention, the 50 washing-water would be charged into the shell 3, as through an inlet 10, and the washing of the dishes effected by causing the water in the shell to be repeatedly lifted and poured upon the dishes in the tray 9, the means which I prefer to employ for this purpose comprising a series of pockets 11 extending longitudinally of the casing 3 and

within the latter, and arranged concentrically of the casing and spaced therefrom a sufficient distance to afford clearance, the pockets 11 being rigidly connected at their rear ends with a head 12 fixed on a shaft 13 journaled in a bearing 13^a in the end 8 of the shell, and at their front ends with a flanged-rim 14 which rests at its annular flange 15 on grooved wheels 16 journaled in the casing 3 on pins 17 provided on the front end of the casing. The pockets 11, rim 14 and head 12 thus form a unitary rotatable member having pockets about its inner surface with openings in its side wall intermediate said pockets, which may be rotated in the casing 3 in any desirable manner, as by means of a crank-handle 18 fixed on a shaft 19 connected with the shaft 13 by sprockets 20 and 21 and a chain 22.

75 In the operation of the machine, the shaft 13 is rotated to the right in Fig. 1 thus causing water to be carried up in the pockets 11, and upon passing above the center of the shaft, the water will discharge upon the 80 dishes (not shown) in the tray 9, for performing the washing operation.

It is preferred that the streams of water which discharge from the pockets 11 when carried up as hereinbefore described be 85 broken up before they fall upon the dishes, in order that the water be evenly distributed over the dishes and effect uniform cleansing of the latter, and further that the dishes and other articles being washed be prevented 90 from projecting into the path of movement of the pockets 11, and to these ends I provide a screen 23 of general cylindrical form, but preferably open along its bottom portion, which is located within the annular series 95 of pockets 11 and extends lengthwise of the machine, the rear end of the screen 23 being connected with a flange 24 provided on a stationary plate 25 supported on the inner end of the shaft 13, the front end of the screen 100 23 with the inwardly-extending flange 26 of a member of L-shape in cross-section and fitting in the opening 6, and the lower edges of the screen with angle-irons 27 spaced apart and extending from end to end of the 105 casing 3 and connected at their opposite ends with the front wall 5 of the casing and the plate 25, respectively.

Below the tray 9 is provided a trough 28, 110 perforated as indicated at 29, and adapted to strain the water before it is again lifted by the water-elevating pockets 11, the

trough 28 extending lengthwise of the machine and being preferably supported, at flanges 30 thereon on the angle-irons 27, this feature of my construction serving to cause 5 the water which is discharged upon the dishes in the tray 9 to be comparatively free of the particles washed from the dishes.

It will be readily understood from the foregoing that by constructing a machine in 10 accordance with my invention, the dishes in the tray 9 may be not only quickly washed, but by reason of the elimination of any obstruction through the center of the machine, may be packed into the tray 9 externally of 15 the machine and the tray of dishes then placed in the machine as illustrated, by introducing the tray through the opening 6 in the shell 3, which is a matter of importance in a machine of this type, as it not only expedites the washing operation, but also minimizes the danger of breaking the dishes. Furthermore, the tray and strainer-trough 20 28 being removable, these parts of the machine may be readily withdrawn from the machine and cleaned, thus rendering the 25 machine highly sanitary.

It may be added that after the dishes have been washed, as hereinbefore explained, the washing-water is preferably drawn off from 30 the casing 3 through a discharge-pipe 31, which preferably empties into a sink, and the casing 3 thereupon charged with rinsing water which is discharged upon the dishes in the tray 9 by the operation of the machine in the manner hereinbefore described.

While I have illustrated and described a specific embodiment of my invention, I do not wish to be understood as intending to limit it thereto, as the same may be variously 40 modified and altered without departing from the spirit of my invention.

What I claim as new and desire to secure by Letters Patent, is—

1. In a dish-washing machine, the combination of a housing containing an opening in one end through which the dishes to be washed are introduced into the housing, means for supporting the dishes in said housing, and a series of water-elevating 45 pockets rotatably supported in said housing.

2. In a dish-washing machine, the combination of a housing containing an opening

in one end through which the dishes to be washed are introduced into the housing, means for supporting the dishes in said 55 housing, and a rotatable water-lifting-pocket-equipped member journaled in said housing and open at its front end to avoid obstruction to the introduction of the dishes into said housing through the opening in 60 the latter.

3. In a dish-washing machine, the combination of a housing containing an opening in one end through which the dishes to be washed are introduced into the housing, 65 means for supporting the dishes in said housing, and a rotatable water-lifting-pocket-equipped member journaled at its rear end in said housing and provided at its front end with a rim-section registering with 70 said opening and at which rim-section said member is rotatably supported at its front end in said housing, for the purpose set forth.

4. In a dish-washing machine, the combination of a housing containing an opening in one end through which the dishes to be washed are introduced into the housing, means for supporting the dishes in said housing, a head journaled in said housing 80 at one end thereof, a rim-section rotatably supported in said housing at its opposite end and registering with said opening, and water-lifting pockets connected with said rim-section and head, for the purpose set 85 forth.

5. In a dish-washing machine, the combination of a housing containing an opening in one end through which the dishes to be washed are introduced into the housing, 90 means for supporting the dishes in said housing, a shaft journaled in said housing, a rotatable water-lifting-pocket-equipped member connected at one end with said shaft and containing an opening at its front 95 end registering with the opening in said housing, and a stationary perforated member supported at one end on said shaft and upon which the water falls before it reaches the dishes, for the purpose set forth.

GEORGE H. HESS.

In presence of—

ALICE MASLEY,
A. NELSON.
